US00D981138S

(12) United States Design Patent (10) Patent No.: US D981,138 S
Zahner (45) Date of Patent: * Mar. 21, 2023

(54) SHOWER CURTAIN(71) Applicant: Zahner Design Group, Ltd., New York, NY (US)(72) Inventor: David Zahner, New York, NY (US)(73) Assignee: Zahner Design Group, Ltd., New York, NY (US)() Term: 15 Years(21) Appl. No.: 29/772,873(22) Filed: Mar. 4, 2021*Related U.S. Application Data

(60) Continuation of application No. 29/732,113, filed on Apr. 21, 2020, now Pat. No. Des. 937,607, which is a continuation of application No. 16/034,812, filed on Jul. 13, 2018, now abandoned, which is a continuation of application No. 14/458,664, filed on Aug. 13, 2014, now Pat. No. 10,045,649, which is a division of application No. 13/564,033, filed on Aug. 1, 2012, now abandoned, which is a continuation of application No. 11/978,532, filed on Oct. 29, 2007, now Pat. No. 8,235,088, which is a continuation of application No. 11/209,334, filed on Aug. 23, 2005, now Pat. No. 7,296,609, which is a continuation of application No. 10/320,340, filed on Dec. 16, 2002, now Pat. No. 6,935,402, which is a continuation of application No. 09/617,402, filed on Jul. 17, 2000, now Pat. No. 6,494,248, and a division of application No. 10/062,588, filed on Jul. 5, 2001, now Pat. No. 7,788,733, which is a continuation of application No. 09/738,555, filed on Dec. 15, 2000, now abandoned, said application No. 10/320,340 is a division of application No. 09/916,603, filed on Jul. 27, 2001, now Pat. No. 7,058,988, which is a continuation of application No. 09/738,545, filed on Dec. 15, 2000, now abandoned.

CLAIM

I claim the ornamental design for a shower curtain, as shown and described.

DESCRIPTION

1 Claim, 1 Drawing Sheet
